CLAIM

The ornamental design for vending machine currency
acceptor, as shown and described.

DESCRIPTION

FIG. 1 is a front perspective view of a vending machine
currency acceptor showing our new design;
FIG. 2 is a front elevational view thereof;
FIG. 3 is a rear elevational view thereof;
FIG. 4 is a right side elevational view thereof, the left
side elevational view being a mirror image thereof; and
FIG. 5 is a top plan view thereof.

FIG. 1

FIG. 4

FIG. 5

FIG. 2

FIG. 3
